UNITED STATES PATENT OFFICE.

ARCHIBALD BARR, OF GLASGOW, SCOTLAND, AND WILLIAM STROUD, OF LEEDS, ENGLAND.

ELECTRICAL APPARATUS FOR TRANSMITTING AND RECEIVING SIGNALS.

1,009,013.

Specification of Letters Patent. Patented Nov. 14, 1911.

Application filed January 28, 1907. Serial No. 354,526.

To all whom it may concern:

Be it known that we, ARCHIBALD BARR, professor of engineering in the University of Glasgow, and residing in Glasgow, in the 5 county of the city of Glasgow, Scotland, and WILLIAM STROUD, professor of physics in the University of Leeds, and residing at Leeds, in the county of York, England, have invented certain new and useful Electrical 10 Apparatus for Transmitting and Receiving Signals, of which the following is a specification.

In one system of telegraphy for conveying information between distant stations, 15 electrical apparatus has been provided comprising a "transmitter" and one or more "receivers." In the type of apparatus to which this invention relates, successive steps in the progressive movement given to an 20 operated member of the transmitter are imparted in steps to a rotor comprised in the receiver, the steps imparted to the rotor corresponding in number and in direction to those given to the operated member of the 25 transmitter.

In the construction of electrical apparatus of this character it has been proposed to provide a number of electro-magnets angularly disposed around an armature shaft set 30 in a plane transverse to the axis of rotation of the armature shaft, in association with a single armature upon which the magnets are adapted to act in succession as they are energized in rotation to turn the armature 35 in a forward or backward direction. In instruments of this kind, invention has been directed toward simplicity of construction and actuation, to which end a simple un- 40 wound armature has been adopted in the construction of the receiver in conjunction with a transmitter consisting of a device for commutating a current so as to cause the electro-magnets of the receiver to be energized in succession in either direction as required. In instruments of this type the construction of receiver adopted is open to some 45 objections partly owing to the electro-magnets being all set in the same transverse plane which causes their fields to intersect and interfere in action with each other, and partly in consequence of the mechanical 50 form of construction involved.

This invention relates to electrical transmitting and receiving apparatus working on 55 the step-by-step system in which electro-

magnets in the receiver are successively energized by the action of the transmitter and the object in view is to produce improved apparatus of this type comprising an improved form of receiver in which the fields of the electro-magnets are in separate planes transverse to the axis of the armature shaft in conjunction with the provision of a separate simple unwound armature for each electro-magnet, with the view of attaining an improved method of action and of producing improvements in the mechanical construction and arrangement of the elements comprising the receiver.

In the construction of apparatus according to this invention, the improved form of receiver consists of a set of motor devices each comprising an electro-magnet having a pair of pole-pieces and a complementary rotary armature, the armatures being carried on a shaft about which the pole-pieces of the electro-magnets are set in separate planes transverse to the axis of the shaft presenting faces concentric thereto, the electro-magnet of each motor device when energized being adapted to act upon its respective armature when the armature is in an appropriate position relative to the pole-pieces and to cause the armature shaft to make a portion of a complete revolution, the 75 motor devices comprised in the set to form the receiver being arranged and provision made so that they are brought into action in rotation to cause the armature shaft to 80 revolve in either a forward or backward direction of rotation as required. To attain this desired disposition of the motor elements, the construction of the receiver may be varied in three ways, first, the axes of the 85 magnets may be set in parallel to each other, and the armatures angularly disposed around the shaft, secondly: the armatures may be set with their axes parallel to each other and the magnets of the series be angularly disposed around the shaft; and thirdly, 90 a combination may be adopted, in which the magnets of the series are angularly disposed and the armatures are also angularly disposed around the shaft.

In the accompanying drawings Figures 1 105 and 2 show in end elevation and plan respectively one form of our improved motor mechanism. Fig. 3 is an illustrative diagram to enable the mode of working of the motor to be more clearly understood. Figs. 110

4 and 5 show an end view and plan of a modified arrangement of the motor mechanism. Figs. 6, 7 and 8 show a modification of the motor mechanism in side elevations 5 and in plan respectively. Figs. 9 and 10 are a side elevation and plan respectively, of a suitable transmitter for the operation of the receiver and Figs. 11 and 12 show developed views of the contact portion of the transmitter.

In Figs. 1 and 2, A, B, and C, are three pairs of pole pieces connected respectively to electro-magnets A¹ B¹ C¹. In arrangement the electro-magnets A¹ B¹ C¹ are set in 15 separate planes along the axis of an armature spindle e, the axes of the pole pieces of the magnets being parallel and being all contained in a plane in which the axis e lies, the faces of the pole pieces being concentric with the axis of the armature spindle e. In Fig. 1, C² indicates the core of the coil C¹, the electro-magnets A¹ and B¹ being similarly constructed. a, b, c, are three armatures fixed to or formed in one piece with 20 the spindle e, the armature a being associated with the pair of pole pieces A, and the armatures b and c, being associated respectively with the pole pieces B and C and the armatures a, b, and c, are angularly disposed 25 relatively to one another around the shaft at equal angles of 120°. By this arrangement each armature is influenced only by the pole pieces associated with it. The pole pieces are shown as being bored out so 30 that their faces take the form of portions of a hollow cylinder, while the armatures a, b and c, are turned cylindrically on their faces so as to lie within the pole pieces with small air gaps.

40 The mode of operation of the mechanism is illustrated in the diagram Fig. 3, in which for clearness, the armatures are exhibited separately, though it is to be understood that, in the form of mechanism at present being described, they have a common axis as shown in Figs. 1 and 2.

The positions in which the motor devices operate are indicated in the diagram Fig. 3. Position 1 represents the stable position 50 when the electro-magnet A¹ is energized, the armature a occupying a position directly between the pole pieces A, A. If now the electro-magnet B is also energized the armatures will assume the position 2, indicated in the 55 diagram. When the current through A is broken, the magnet B only being energized, position 3 is assumed and so on successively through positions 4, 5, 6, when the magnets are energized in the order A, A and B, B, B and C, C, C and A, and so back to the position 60 1 when A alone is energized. In this way the spindle e is caused to rotate 180° by six successive steps. It will be evident that if the order of energizing be reversed 65 the armatures will rotate in the opposite di-

rection, assuming such positions as is shown in the order 1, 6, 5, 4, 3, 2. In other cases we may energize the magnets singly in which cases the rotor will take up the successive positions represented as position 1, position 70 3, position 5.

Figs. 4 and 5 show an alternative arrangement in which the axes of the pole pieces are disposed at 120° apart while the armatures a, b, c, have their axes parallel to one another, but still retaining the chief feature of the invention, namely, the placing of the magnets in different planes transverse to the axis and providing a separate armature for each magnet.

Figs. 6, 7 and 8 show a modification of the motor mechanism of the receiver, wherein each of the armatures a, b, c, has four arms instead of two, the arms of b being at 30° to those of a and c and those of c at 30° to those of b and a. In this case the rotor will make one complete revolution in twelve steps if the magnets are energized singly or in twenty-four steps if the magnets are energized in the order A, A and B, B, B and C, C, C and A.

Any type of transmitting instrument that is adapted to commute or distribute an electric current so as to cause it to flow through the coils of the electro-magnets of the receiving instrument in the required order may be used to operate the receiving instruments. One form of transmitter suitable for operation by hand is illustrated in 95 Figs. 9, 10, 11 and 12. In these figures F 100 is a handle on the spindle L on which a pinion G is carried which gears with a wheel H carried on the spindle of a drum E. In the arrangement shown the spindle of the handle is in two parts L and L¹, and these 105 are connected by a coupling K. This arrangement is merely for convenience, so as to allow the spindle L to be carried on the outer case of the transmitter while the spindle L¹ is mounted on the framework of the 110 internal mechanism. In these figures E is a drum of insulating material, such as glass, carrying upon its cylindrical surface contact pieces A², B², C², which are connected to a 115 piece E¹.

An arrangement of contact pieces suitable for working receivers in the manner illustrated in Fig. 3 is shown developed in Fig. 12. In Fig. 12, A⁴, B⁴, C⁴, are three suitable brushes arranged to make connection with the parts A², B², C², respectively, and these brushes A⁴, B⁴ and C⁴ are electrically connected with the magnet coils A¹ B¹ C¹, respectively. Current from a suitable generator is brought to the brush E² and is thus 120 distributed to the magnets of the motor mechanism in proper succession as the commutator is revolved, the current being then 125 conducted back from the magnets to the generator, the magnets being energized in 130

the order A, A and B, B and C, etc., or in the order C, C and B, B and A, etc. When on the other hand, the magnets are to be energized in the order A, B and C, etc., or 5 in the order C, B, A, etc., the arrangement shown in Fig. 11 may be used. The armature will then take the successive positions illustrated diagrammatically by positions 1, 3 and 5 in Fig. 3.

10 In instruments of this type the transmitter may be adapted to be operated by hand or it may be automatically actuated when the motions of some mechanism are to be indicated, and the rotor of the receiver 15 is adapted to impart step-by-step movements to a pointer, a drum, a dial or other indicator in a forward or backward direction as required for indicating orders, ranges for gun control or other communication in a 20 manner common to apparatus of this type. In the drawings, see Figs. 2 and 8, a toothed wheel e^1 is shown fitted to the armature shaft e which may for example be arranged to drive a counter or other indicating 25 mechanism suitable say for indicating ranges at a gun, the receiver being operated by a transmitter located at a distant station.

We claim as our invention:

1. Electrical transmitting and receiving 30 apparatus of the type working on the step-by-step system consisting of a receiver having a set of motor devices each of which comprises an electro-magnet having a pair 35 of pole pieces and a complementary rotary unwound armature, the armatures being carried on a shaft and the pole pieces and armatures presenting faces concentric to the axis of the shaft, the motor devices being set in separate planes transverse to the axis 40 of the shaft, the electro-magnet and armature of each motor device at any instant being at a different angle to each other than the electro-magnet and armature of any other motor device whereby when energized 45 each electro-magnet is adapted to act upon its respective armature and cause the armature shaft to make a portion of a complete revolution, in combination with a transmitter adapted to commute a current for 50 energizing the magnets in rotation, for the purpose set forth.

2. Electrical transmitting and receiving 55 apparatus of the type working on the step-by-step system consisting of a receiver having a set of motor devices each of which comprises an electro-magnet having a pair 60 of pole pieces and a complementary rotary unwound armature, the armatures being carried on a shaft and the pole pieces and armatures presenting faces concentric to the axis of the shaft, the motor devices being set in separate planes transverse to the axis of the shaft, the electro-magnet and armature of each motor device at any instant being 65 at a different angle to each other than

the electro-magnet and armature of any other motor device whereby when energized each electro-magnet is adapted to act upon its respective armature and cause the armature shaft to make a portion of a complete 70 revolution, in combination with a transmitter adapted to commute a current for energizing the magnets in rotation, for the purposes set forth.

3. Electrical transmitting and receiving 75 apparatus of the type working on the step-by-step system consisting of a receiver having a set of three motor devices each of which comprises an electro-magnet having a pair 80 of pole pieces and a complementary rotary unwound armature, the armatures being carried on a shaft and the pole pieces and armatures presenting faces concentric to the axis of the shaft, the motor devices being set in separate planes transverse to 85 the axis of the shaft, the electro-magnet and armature of each motor device at any instant being at a different angle to each other than the electro-magnet and armature of any other motor device whereby when energized 90 each electro-magnet is adapted to act upon its respective armature and cause the armature shaft to make a portion of a complete revolution, in combination with a transmitter adapted to commute a current for energizing the magnets in rotation, for the purposes set forth.

4. Electrical transmitting and receiving 100 apparatus of the type working on the step-by-step system consisting of a receiver having a set of motor devices each of which comprises an electro-magnet having a pair 105 of pole pieces and a complementary rotary unwound armature having radial arms in balanced arrangement, the armatures being carried on a shaft and the pole pieces and armatures presenting faces concentric to the axis of the shaft, the motor devices being set in separate planes transverse to the axis of the shaft, the electro-magnet and armature 110 of each motor device at any instant being at a different angle to each other than the electro-magnet and armature of any other motor device whereby when energized each electro-magnet is adapted to act upon its respective armature and cause the armature 115 shaft to make a portion of a complete revolution, in combination with a transmitter adapted to commute a current for energizing the magnets in rotation, for the purposes set forth.

5. Electrical transmitting and receiving 120 apparatus of the type working on the step-by-step system consisting of a receiver having a set of motor devices each of which 125 comprises an electro-magnet having a pair of pole pieces and a complementary rotary unwound armature having two radial arms in balanced arrangement, the armatures being carried on a shaft, and the pole pieces 130

and armatures presenting faces concentric to the axis of the shaft, the motor devices being set in separate planes transverse to the axis of the shaft, the electro-magnet and armature of each motor device at any instant being at a different angle to each other than the electro-magnet and armature of any other motor device whereby when energized each electro-magnet is adapted to act upon its respective armature and cause the armature shaft to make a portion of a complete revolution, in combination with a transmitter adapted to commutate a current for energizing the magnets in rotation for the purpose set forth.

6. Electrical transmitting and receiving apparatus of the type working on the step-by-step system consisting of a receiver having three motor devices each of which comprises an electro-magnet and a complementary rotary unwound armature, the armatures being carried on a shaft about which the motor devices are set in separate planes transverse to the axis of the shaft, the pole pieces of the magnets of the series being set in one plane passing through the axis of the shaft and the armatures angularly disposed around the shaft, in combination with a transmitter adapted to commutate a current for energizing the magnets in rotation, for the purposes set forth.

7. Electrical transmitting and receiving apparatus of the type working on the step-by-step system consisting of a receiver having a set of motor devices each of which comprises an electro-magnet and a complementary rotary unwound armature having radial arms in balanced arrangement, the armatures being carried on a shaft about which the motor devices are set in separate planes transverse to the axis of the shaft, the pole pieces of the magnets of the series being set in one plane passing through the axis of the shaft and the armatures angularly disposed around the shaft, in combination with a transmitter adapted to commutate a current for energizing the magnets in rotation, for the purposes set forth.

tate a current for energizing the magnets in rotation, for the purposes set forth.

8. Electrical transmitting and receiving apparatus of the type working on the step-by-step system consisting of a receiver having a set of motor devices having a common shaft and each of which comprises an electro-magnet and a complementary rotary unwound armature having two radial arms formed in a piece extending across the shaft, about which shaft the motor devices are set in separate planes transverse to the axis of the shaft, the pole pieces of the magnets of the series being set in one plane passing through the axis of the shaft and the armatures angularly disposed around the shaft, in combination with a transmitter adapted to commutate a current for energizing the magnets in rotation, for the purposes set forth.

9. Electrical transmitting and receiving apparatus of the type working on the step-by-step system consisting of a receiver having a set of motor devices each of which comprises an electro-magnet and a complementary rotary unwound armature, the armatures being carried on a shaft about which the motor devices are set in separate planes transverse to the axis of the shaft, the pole pieces of the magnets of the series being set in one plane passing through the axis of the shaft, the individual pairs having their poles diametrically arranged to another on opposite sides of the shaft, the armatures being angularly disposed around the shaft, in combination with a transmitter adapted to commutate a current for energizing the magnets in rotation, for the purposes set forth.

In witness whereof we have hereunto set our hands in the presence of two witnesses.

ARCHIBALD BARR.
WILLIAM STROUD.
